UNITED STATES PATENT OFFICE

168,596

CLASP DEVICE FOR A MULTIPLE STRAND BRACELET OR THE LIKE

Robert Rubel, New York, N. Y.

Application November 27, 1951, Serial No. 17,531

Term of patent 3½ years

(CL. D45—1)

To all whom it may concern:

Be it known that I, Robert Rubel, a citizen of the United States, residing in New York city, in the county of New York and State of New York, have invented a new, original, and ornamental Design for a Clasp Device for a Multiple Strand Bracelet or the like, of which the following is a specification, reference being had to the accompanying drawing, forming part thereof.

Fig. 1 is a top plan view of a clasp device for a multiple strand bracelet or the like, showing my design,

Fig. 2 is an edge view thereof.

I claim:

The ornamental design for a clasp device for a multiple strand bracelet or the like, substantially as shown.

ROBERT RUBEL.
